UNITED STATES PATENT OFFICE.

THOMAS G. BOWERS, OF NEW HAVEN, CONNECTICUT.

DESIGN FOR A SHOULDER-BRACE.

45,368.

Specification for Design.

Patented Mar. 10, 1914.

Application filed October 6, 1913. Serial No. 793,771. Term of patent 7 years.

To all whom it may concern:

Be it known that I, THOMAS G. BOWERS, a citizen of the United States, residing at New Haven, in the county of New Haven and State of Connecticut, have invented a new, original, and ornamental Design for Shoulder-Braces, of which the following is a specification, reference being had to the accompanying drawing, forming part thereof.

The figure is a rear view of a shoulder brace embodying my new design.

I claim—

The ornamental design for a shoulder brace, as shown.

THOS. G. BOWERS.

Witnesses:

FREDERIC C. EARLE,
MALCOM P. NICHOLS.
